THERMOSTAT.

1,218,167.

Specification of Letters Patent.

Patented Mar. 6, 1917.

Application filed November 16, 1915. Serial No. 61,850.

To all whom it may concern:

Be it known that I, HAROLD J. CARMODY, a citizen of the United States, residing at New York, borough of Brooklyn, in the county of Kings and State of New York, have invented certain new and useful Improvements in Thermostats, of which the following is a full, clear, and exact description.

10 My invention relates to thermostats, my more particular purpose being to group the various parts of the thermostatic mechanism into compact form and to give them such appropriate shapes as to facilitate their use, 15 collectively, as a single small article of manufacture, easily placed in position where it is to be used, and possessing many advantages.

While my thermostat admits of general 20 use, it is especially adapted for service upon automobile radiators and analogous structures.

Reference is made to the accompanying drawing forming a part of this specification, 25 and in which like letters indicate like parts in all of the figures.

Figure 1 is an elevation of a radiator upon which one of my improved thermostats is mounted.

30 Fig. 2 is a fragmentary view partly broken away and partly in section, showing the thermostatic mechanism supported upon the radiator.

Fig. 3 is a view of the thermostat and is 35 partly in elevation and partly broken away.

Fig. 4 is a substantially central section through the mechanism of the thermostat.

Fig. 5 is a fragmentary section through the casing, and shows the gearing of the 40 thermostatic mechanism.

Fig. 6 is a section on the line 6-6 of Fig. 4, looking in the direction of the arrows.

Fig. 7 is a fragmentary section, showing in detail the manner in which the thermostatic static springs are each secured to the shaft.

Fig. 8 is a section on line 8-8 of Fig. 3.

The body of a radiator is shown at 8, and at 9 appears the radiator shell. The casing of the thermostat is shown at 10, and has 50 the general proximate form of a sector. Secured to the casing 10 is a tubular member

11, provided with perforations 12 and thus having a foraminous form. This tubular member 11 is provided with a closed end 13, and because of its function is designated as 55 an armor tube. The armor tube is provided with a threaded portion 14 of greater diameter than the body portion of the tube, and this threaded portion is fitted into and extends through the radiator shell 9, the latter 60 for this purpose being provided with a threaded opening 15. Encircling the armor tube 11 is a fiber washer 16 and a metallic washer 17, which are squeezed tightly between the shell 9 and the casing 10. For 65 this purpose the casing is merely turned, so as to rotate the armor tube and parts carried within it, the threaded portion 14 serving the purpose of a screw.

Disposed concentrically within the armor 70 tube 11 and concentrically fitting closely within the same is a tubular barrel 18, provided with a head 19 and secured rigidly to the casing 10. Located within the barrel 18 and extending across the same at a point 75 near the head 19 is a cross bar 20, serving as a bearing. A shaft 21 extends axially into the barrel 18, and is provided with a reduced portion 22 extending through a hole in the cross bar and serving as a journal neck. The casing 10 is provided with a pair 80 of journal plates 23, 24, disposed parallel with each other. The shaft 21 extends through a hole in the plate 23, and is provided with a reduced portion 25 which serves 85 as a journal neck, and extends through a hole in the plate 24.

Mounted rigidly upon the shaft 21 is a gear wheel 26, and meshing with this gear wheel is a pinion 27 which is mounted rigidly upon a stub shaft 28. This shaft extends through holes in the journal plates 23 and 24. A pointer 29 is provided with a collar portion 30, which is secured rigidly 90 upon the stub shaft 28, so that the pointer 95 is moved angularly around as the stub shaft 28 is rocked.

A number of composite strips 31, are each made of steel and brass or of any other two metals in which the coefficient of thermal expansion is different. These strips are each coiled into helical form as shown. Each 100

strip is provided with a straight end portion 32, which extends diametrically through a slot in the shaft 21, as shown in Fig. 7. Each strip is also provided with an end portion 33, which extends tangentially outward through a slot in the wall of the barrel 18 and is soldered or brazed as shown at 32.

Owing to the differential expansion and contraction of the component metals of the strip 21, the shaft 21 is rocked or turned slightly whenever the barrel 18 is heated or cooled, and the pointer 29, by virtue of the ratio of the gearing contracting it, is caused to rock slowly within reasonable limits.

15 The casing 10 is provided with a back plate 33 and with a front plate 34, the front plate being held in position by screws 35. The front plate carries a flange 36 which is bent slightly outward and overlaps the 20 edges of a glass plate 37 serving the purpose of a window.

Extending through oppositely disposed portions of the wall of the casing 10 are a pair of sleeves 38, 39 of insulating material, 25 preferably fiber or hard rubber. Extending through these sleeves are two screws 40, 41. Revolvably mounted upon the screw 40 and adapted to abut the ends of the sleeve 38 are two nuts 42, 43. Similarly the screw 30 41 carries two nuts 44, 45 revolvably mounted upon it and adapted to abut the ends of the sleeve 39. The screws 40 and 41 are thus each adjustable in the direction of its own length. Spring contact members 46, 47, each 35 having substantially a V-form, are carried by the screws 40, 41, and located upon the ends thereof extending within the casing.

Disposed adjacent the contact member 46 and 47 are legends Heat—Boiling and 40 Cold—Freezing, together with two arrows, the purpose of all of which is to assist the operator in ascertaining the position of the pointer 29 and the direction of its travel at any particular instant.

45 An insulated wire 48 extends from the screw 40 to the screw 41, and connected to the screw 41 is another insulated wire 49. An insulated wire 50 is connected directly to the casing 10. Whenever the pointer 29 50 comes into engagement with either contact member 46 or 47 an electric circuit is completed in the usual or any desired manner, and this electric circuit may include any convenient alarm mechanism adapted to be 55 operated by an electric current.

In the particular device here illustrated, I show three of the helical strips 31. This promotes accuracy, as the shaft 21 is rocked or turned to an extent commensurate with 60 the mean temperature of the three strips. By use of a plurality of the strips 31, the shaft 21 is under normal conditions held quite securely, and the pointer 29 is not disturbed by accidental jars and shocks.

In order to assemble the parts, the cross 65 bar 20 is placed within the barrel 18 and soldered or brazed in position. Next the composite strips 31 are severally secured upon the shaft 21 as indicated in Fig. 7 and as above described. The shaft 21, carrying the 70 composite strips, is thrust into the barrel 18 and the reduced portion 22 is guided through the hole in the cross bar, as shown in Fig. 4. Then the outer or free ends of the composite strips are brought out through holes in the 75 wall of the barrel and soldered, as indicated in Fig. 6. The gear wheel 26 is placed within the casing 10, between the journal plates 23, 24, and the free end of the shaft 21 is thrust through the gear wheel 26 and 80 the journal plates. The barrel 18 is next brazed or soldered upon the casing 10 and the armor tube 11 is next slipped over the barrel, spaced concentric to the latter, and brazed or soldered to the casing. The various 85 other parts are added in any manner desired, no special skill being requisite for this purpose.

The operation of my device is as follows:—The parts being assembled and arranged as described, and the wires 49, 50 being connected with a source of electricity and with an alarm, the mechanism is ready for use. Normally the position of the pointer 29 is somewhere between the contact members 46 and 47. Owing to variations in temperature, to which the radiator 9 may be subjected, however, the pointer may be brought into engagement with one or the other of the contact members 46, 47, so as to complete the electric circuit and actuate the alarm. The parts are so proportioned and arranged that when the barrel 18 and parts connected with it are subjected to a heat equal to that of boiling water, the pointer engages the contact member 46, but if the temperature of the barrel and parts connected with it be lowered to the freezing point of water, the pointer is brought into engagement with the 100 contact member 47.

The foraminous character of the armor tube 11 promotes access, to the barrel 18, of steam or water, as the case may be, contained within the radiator. The barrel 18 105 is both water tight and steam tight.

I do not limit myself to the exact construction shown, as variations may be made therefrom without departing from the spirit of my invention, the scope of which is commensurate with my claims:—

I claim:—

In a thermostat the combination of a casing, indicating mechanism mounted within said casing, a steam-tight barrel secured to 125 said casing and adapted to extend into a radiator so as to support said casing, a revolvable shaft connected to said indicating mech-

anism for the purpose of actuating the same, said shaft extending from said casing into said barrel, and a plurality of separate strips located within said barrel, each strip being connected at one of its ends to said shaft and at the other of its ends to said barrel, said strips being heat-controlled and spaced

equidistant in order to equalize the effect of the heat at different points within said barrel.

10

In testimony whereof, I have signed my name to this specification.

HAROLD J. CARMODY.
